DIRECTIVE ULTRA HIGH FREQUENCY
ANTENNA

William S. Halstead, Purchase, N. Y., assignor, by
mesne assignments, to Farnsworth Research
Corporation, a corporation of Indiana

Application February 9, 1946, Serial No. 646,630

9 Claims. (Cl. 250—33.65)

1

This invention relates generally to antennae for receiving ultra-high frequency electromagnetic waves, and more particularly relates to a directive antenna array arranged to be tuned to waves of different wave length.

Antenna arrays of the type which comprise one or more directors, a reflector and a principal dipole are known in the art. Such antenna arrays show an appreciably higher gain than a single dipole. They have a better directivity and a large front-to-back ratio, that is, they will receive a wave impinging on the front of the array with a high gain while substantially suppressing waves arriving from the opposite direction. An antenna array which comprises a director, a reflector and a principal dipole is, therefore, well suited for the reception of ultra-high frequency carrier waves modulated, for example, in accordance with a television signal.

It is well known that ultra-high frequency waves are reflected by comparatively small obstacles, such as buildings. Since the carrier waves used for the transmission of television signals are all within the ultra-high frequency range, it is very desirable to provide a television receiving antenna which has a good directivity and a large front-to-back ratio so that it will receive the desired signal from the transmitting antenna while rejecting undesired waves. However, a conventional antenna array of this type may be used only for receiving carrier waves of one frequency or waves within a very narrow frequency band. It is, therefore, desirable to provide an antenna array of the type referred to which may be tuned to different wave lengths and, furthermore, to provide means for rotating the array so that carrier waves from different stations may be received with one antenna or one antenna array.

It is an object of the present invention, therefore, to provide, in an antenna array of the type comprising a plurality of spaced dipoles, means for tuning the array to modulated carrier waves of different wave lengths.

A further object of the invention is to provide an antenna array for receiving ultra-high frequency electromagnetic waves comprising a director, a reflector and a principal dipole which may be tuned and rotated to any angular position.

In accordance with the present invention, there is provided an antenna array for ultra-high frequency electromagnetic waves comprising a plurality of extensible conducting members

2

arranged substantially parallel to each other and means for simultaneously extending or retracting the extensible members. In this manner the effective electrical length of the antenna array is varied.

For a better understanding of the invention, together with other and further objects thereof, reference is made to the following description, taken in connection with the accompanying drawings, and its scope will be pointed out in the appended claims.

In the accompanying drawings:

Fig. 1 is a plan view of an antenna array embodying the present invention;

Fig. 2 is a front elevational view of the antenna array of Fig. 1;

Fig. 3 is a sectional view on enlarged scale of the antenna housing taken on line 3—3 of Fig. 1;

Fig. 4 is a sectional view on enlarged scale of one of the extensible arms of the principal dipole of the antenna array taken on line 4—4 of Fig. 1;

Fig. 5 is a cross-sectional view on enlarged scale of the extensible principal dipole arm taken on line 5—5 of Fig. 4;

Fig. 6 is a front elevational view, partly in section, and on enlarged scale of the director dipole of the antenna array taken on line 6—6 of Fig. 1;

Fig. 7 is a plan view of a modification of the antenna array of the invention;

Fig. 8 is a sectional view on enlarged scale of the antenna housing taken on line 8—8 of Fig. 7; and

Fig. 9 is a diagram of a control circuit for energizing the motors for rotating and tuning the antenna array.

Referring particularly to Figs. 1 and 2 of the drawings, there is illustrated antenna array 10 comprising principal dipole 11, director dipole 12 and reflector dipole 13 which are arranged substantially parallel to each other. Principal dipole 11, director dipole 12 and reflector dipole 13 comprise each two extensible or telescoping arms 15, 15; 16, 16; and 17, 17; respectively. Director dipole 12 and reflector dipole 13 are spaced a predetermined distance from principal dipole 11 by means of outer spacing members 20, 21 and intermediate spacing members 22. Spacing members 20, 21 and 22 are made of insulating material.

Arms 15, 15 of principal dipole 11 and spacing members 22 are supported by upper housing 23 rotatably mounted on lower stationary housing

24. Lower stationary housing 24 is provided with downwardly extending sleeve 25 (Fig. 3) arranged for receiving tubular member 26 which may be secured to sleeve 25 by set screws 27. Tubular member 26 is supported in an upright position in a suitable manner such as by supporting members 28 (Fig. 2).

Principal dipole 11, director dipole 12 and reflector dipole 13 form an antenna array having a gain which is approximately 6 to 7 decibels higher than that of a single dipole. While a single dipole will receive waves from opposite directions with equal gain, antenna array 10 has a front-to-back ratio of 15 to 25 decibels. By way of example, the spacing between principal dipole 11 on the one hand, and director dipole 12 and reflector dipole 13, on the other hand, may be approximately one-eighth of the wave length of the modulated carrier wave to be received. The effective electrical length of principal dipole 11 should be equal to one-half the wave length of the wave to be received. The effective electrical length of director dipole 12 should be slightly less than that of principal dipole 11, while the effective electrical length of reflector dipole 13 should be slightly more than half a wave length of the wave to be received. When antenna array 10 is arranged in this manner, director dipole 12 and reflector dipole 13 are parasitically excited. It is well known in the art that the dipoles of antenna array 10 may have different electrical lengths and different spacings from those given above by way of example.

Since the effective electrical length of dipoles 11, 12 and 13 can be one-half wave length only for one frequency, means are provided in accordance with the present invention for varying the electrical length of the dipoles, thereby to tune antenna array 10 to waves of different lengths. As illustrated in Fig. 3, there are provided reversible electric motors 30 and 31 for rotating antenna array 10 and for extending or retracting arms 15, 15 of principal dipole 11. Reversible electric motor 30 is mounted in lower stationary housing 24 by disc 32 resting on shoulder 33 of lower housing 24. Electric motor 30 is arranged for rotating upper housing 23, and to this end, motor 30 drives pinion 34 through a reduction gear train indicated at 35. Pinion 34 meshes with internal gear 39 secured to upper housing 23 by set screws 36. Upper housing 23 rests on shoulder 37 of lower housing 24 and is rotatably secured thereto by pins 38 engageable with annular recess or race 40.

Accordingly, it will be evident that when electric motor 30 is energized to rotate in either one of two directions, pinion 34 will rotate internal gear 39. Therefore, upper housing 23 will rotate with respect to lower stationary housing 24 in a direction depending upon the direction of rotation of electric motor 30. The control circuit for energizing electric motor 30 will be explained hereinafter.

Reversible electric motor 31 is provided in upper housing 23 and is arranged for extending or retracting arms 15, 15 of principal dipole 11. Electric motor 31 is connected to a power source by leads, not illustrated, which are connected, in turn, to spring contacts 41, 42 and 43, secured to plate 44 on stationary housing 24. Spring contacts 41, 42 and 43 bear on and slide over contact 45 and annular slip-rings 46 and 47 respectively. Conductors 45, 46 and 47 are arranged in insulating disc 48 mounted in upper housing 23 and secured thereto by set screws 50. Leads 75

51, 52 and 53 are connected to conductors 45, 46 and 47 respectively, cooperating with spring contacts 41, 42 and 43.

When reversible electric motor 31 is energized to rotate in either one of two directions, motor shaft 55 is rotated accordingly. Motor shaft 55 bears a worm, not shown in the drawings, which engages with gear 56 secured to insulating drive shaft 57. Ball bearing 58 is provided for supporting the free end of motor shaft 55. Insulating drive shaft 57 is rotatably supported by ball bearings 60 and 61. Upper housing 23 has two horizontally extending sleeves 62 and 63 for supporting outer tubes 64 of dipole arms 15, 15 of principal dipole 11.

Each outer tube 64 of one of the dipole arms 15, 15 is mounted in an insulating block 65 supported in turn by sleeves 62 and 63, respectively. Set screw 66 secures insulating block 65 to sleeve 62 while set screw 67, which extends through set screw 66, locks outer tube 64 with insulating block 65. The outer tube 64 of the left hand dipole arm 15 is secured to sleeve 63 in the same manner as the outer tube 64 of the right hand dipole arm so that further explanation is not necessary. Housing cover 68 closes the upper portion of housing 23.

Insulating drive shaft 57 is connected to worms 70, extending through outer tube 64, by means of sleeves 71. Ball bearings 60 and 61 are provided with insulating washers 72 so that worms 70 are electrically insulated from ball bearings 60 and 61 respectively.

When reversible electric motor 31 is energized to rotate in either one of two directions, motor shaft 55 and gear 56 are rotated for driving shaft 57. Hence, worms 70 are rotated in a predetermined direction to extend or retract arms 15, 15 of principal dipole 11 in unison in a manner presently to be explained.

Telescoping dipole arms 15, 15 are identical in construction, one dipole arm 15 being illustrated particularly in Fig. 4. Dipole arm 15 comprises outer stationary tube 64 and inner tube 75 arranged to be retracted and extended into and out of stationary tube 64 by means of worm 70. To this end, bushing 76 is secured to the free end of inner tube 75. Bushing 76 is provided with internal gear 77 arranged to engage with worm 70. As shown particularly in Fig. 5, bushing 76 has a key 78 engaging with keyway 80 in outer tube 64 to prevent rotation of inner tube 75 with respect to outer stationary tube 64.

Spring 81 bears against insulating block 65, while spring 82 encircles reduced end portion 83 of worm 70 and bears against disc 84 secured to end portion 83.

It may be assumed that worm 70 is rotated by electric motor 31 in a direction to draw inner tube 75 toward the left of Fig. 4. Accordingly, bushing 76 is advanced toward the left until it compresses spring 81. Further rotation of worm 70 will disengage bushing 76 from worm 70 whereupon the inward movement of inner tube 75 stops.

When electric motor 31 is now energized to rotate in the opposite direction, spring 81 will urge bushing 76 into engagement with worm 70. Inner tube 75 is then advanced toward the right of Fig. 4 until bushing 76 compresses spring 82. Further rotation of worm 70 will disengage it from bushing 76 whereupon the outward movement of inner tube 75 is arrested. When electric motor 31 is again energized to rotate in the opposite direction, bushing 76 is urged into engagement with

worm 10 by spring 82, and inner tube 75 is advanced toward the left in the manner previously explained.

From the above description it will be evident that telescoping arms 15, 15 are extended or retracted in unison. For extending and retracting dipoles 12 and 13, inner tube 75 of dipole arm 15 is rigidly secured to outer insulating and spacing member 21 (Figs. 1 and 4). The construction of one of the telescoping arms 16, 16 of director dipole 12, which are identical to arms 17, 17 of reflector dipole 13, is illustrated in Fig. 6. Arm 16 comprises outer stationary tube 85 fixed to spacing member 22 and inner tube 86 arranged to be retracted and extended into and out of outer stationary tube 85. Inner tube 86 is rigidly connected with outer insulating and spacing member 21.

Hence, it will be seen that when inner tube 75 is extended or retracted with respect to outer stationary tube 64 of principal dipole 11, insulating members 20 and 21 will be moved accordingly. Since inner tube 86 of director dipole 12 is secured to insulating member 21, as is the inner tube of reflector dipole 13, director dipole 12 as well as reflector dipole 13 will be extended or retracted in unison with principal dipole 11. Accordingly, dipoles 11, 12 and 13 may be extended and retracted in unison by energizing electric motor 31. Thus, antenna array 10 may be tuned to different wave lengths corresponding to the wave length of the carrier wave to be received. Antenna array 10 will receive waves arriving from the direction indicated by arrows 88 in Fig. 1. Waves arriving from the opposite direction will be substantially suppressed by antenna array 10.

Electric motor 30 preferably is arranged for rotating upper housing 23 and antenna array 10 through an angle of at least 360 degrees so that antenna array 10 may be rotated to receive electromagnetic waves arriving from any direction of the azimuth. Alternatively, if reflector 17 is omitted, antenna array 10 may be rotated through an angle of slightly over 180 degrees.

The modulated carrier wave which is intercepted by antenna array 10 may be obtained through output leads 90, 90 connected by clamps 91, 91 to dipole arms 15, 15 of principal dipole 11 (Fig. 1). Output leads 90, 90 may take the form of a transmission line to reduce the attenuation losses of the signal. It is also feasible to provide slip rings cooperating with stationary contacts connected to antenna feeder line 90, 90 to allow for continuous rotation of antenna array 10. Since dipoles 12 and 13 act as parasitic elements, they are normally not connected to principal dipole 11 through leads or transmission lines.

Referring now to Fig. 7, there is illustrated a modified embodiment of the invention comprising antenna array 100. Antenna array 100 includes principal dipole 101, director dipole 102 and reflector dipole 103. Dipoles 101, 102 and 103 are arranged to have their electrical lengths varied and furthermore, the spacing between dipoles 101, 102 and 103 is also made variable. To this end, dipoles 101, 102 and 103 are spaced by extensible insulating connecting members 104, 105 and 106, each comprising two telescoping arms. Principal dipole 101 and extensible connecting members 105 are supported by housing 107. The modulated carrier wave received by antenna array 100 may be obtained from output leads 110 connected by clamps 111 to principal

dipole 101. Output leads 110 may again take the form of a transmission line to reduce signal losses.

Referring now to Fig. 8, there are illustrated two reversible electric motors 112 and 113 arranged, respectively, for extending and retracting principal dipole 101 and for extending and retracting connecting members 105. Reversible motor 112 is supported in housing 107 and is arranged to rotate worms 114 in the manner described in connection with Figs. 1 to 6, through the intermediary of a gear train housed in gear box 115. Worms 114 extend through outer stationary tubes 116 of principal dipole 101. Worms 114 are arranged to extend and retract inner tubes 117 (Fig. 7) in the manner explained in connection with antenna array 10 of Fig. 1. Similarly motor 113 is arranged to extend and retract the extensible arms of connecting members 105.

Accordingly the effective electrical length of dipoles 101, 102 and 103 may be varied by energizing electric motor 112 and their relative spacing may be varied by controlling electric motor 113. Thus, the spacing between dipoles 101, 102 and 103 may be varied always to conform to a predetermined fraction of the modulated carrier wave to be received. At the same time the effective electrical length of dipoles 101, 102 and 103 may be varied to conform to another predetermined fraction of the wave length of the same carrier wave to be received.

Housing 107 may be rotated by electric motor 120 arranged to drive gear 121 meshing with gear ring 122 secured to tube 123. Tube 123 may be integral with or secured to housing 107. Inner tube 124 arranged in outer tube 123 is stationary. Disc 125 is secured to the top of stationary tube 124 and has attached thereto spring contacts 126, 127, 128, 129 and 130 cooperating, respectively with annular conductors 132 and 133, contact 134, and annular conductors 135 and 136. Conductors 132 to 136 are arranged in insulating plate 137 secured to housing 107. The electric power supply is connected to motors 112 and 113 through cables 140, 141 connected to spring contacts 126 to 130. Leads 142 and 143 are connected respectively to motors 113 and 112 and to annular conductors 132 to 136.

Referring now to Fig. 9, there is illustrated schematically a control circuit for energizing electric motors 112, 113 and 120. Electric motors 112, 113 and 120, which are reversible, are shown schematically in Fig. 9. By means of switches 144, 145 and 146, 147 respectively, electric motors 112 and 113 may be energized to rotate in either one of two predetermined directions. Similarly, electric motor 120 may be energized to rotate in either one of two predetermined directions by switches 148 and 149. Motor 112 rotates as long as either switch 144 or 145 is closed, while electric motors 113 and 120 also rotate as long as either of the switches 146 or 147 or either of the switches 148 or 149, respectively, is closed. As explained hereinbefore, electric motor 112 will not cause further movement of inner tube 117 of principal dipole 101 when inner tube 117 is either in its fully extended or in its fully retracted position. The same applies to electric motor 113 which will not cause further motion of connecting members 105 when their inner tubes are in their fully extended or in their fully retracted positions. Thus each of the motors 112, 113 and 120 may be controlled independently thereby to vary the

electrical length of dipoles 101, 102 and 103; their relative spacing and the angular position of antenna array 100.

It is also feasible to energize and de-energize electric motors 112 and 113 simultaneously, for example, by means of two common switches. In that case, the gear ratio between the motors and their driven members should be such that the ratio between the effective electrical length of dipoles 101, 102 and 103 and their relative spacing always remains constant.

Electric motors 30 and 31 (Fig. 3) may also be controlled by means of an electric circuit such as that illustrated in Fig. 9. Thus electric motors 112 and 113 may be replaced by motors 30 and 31 in the circuit of Fig. 9. These motors may be controlled by switches 144 to 147 in the manner already described.

The supporting structure and mechanism for adjusting the antenna provided in accordance with this invention is disclosed herein purely by way of example as it is not intended that the invention shall be limited to such structure and mechanism. It will be obvious to those skilled in the art that there are many alternative supporting structures and adjusting mechanisms which may be substituted for those described herein.

While there has been described what are at present considered the preferred embodiments of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. An antenna array for ultra-high frequency electromagnetic waves comprising a plurality of extensible dipoles arranged substantially parallel to each other, means for simultaneously extending and retracting said dipoles, thereby to vary the effective electrical length of said dipoles, extensible connecting members for spacing said dipoles, and means for simultaneously extending and retracting said connecting members, thereby to vary the relative spacing of said dipoles.

2. An antenna array for ultra-high frequency electromagnetic waves comprising a principal dipole, a director dipole, and a reflector dipole, each of said dipoles including two telescoping arms, extensible insulating connecting members for spacing said dipoles substantially parallel to each other, means for simultaneously extending and retracting said arms, thereby to vary the effective electrical length of said dipoles, and means for simultaneously extending and retracting said members, thereby to vary the spacing between said dipoles.

3. An antenna array for ultra-high frequency electromagnetic waves comprising a principal dipole, a director dipole, and a reflector dipole, each of said dipoles including two telescoping arms, extensible insulating connecting members for spacing said dipoles substantially parallel to each other, means for extending and retracting said arms in unison, thereby to vary the effective electrical length of said dipoles, means for extending and retracting said members in unison, thereby to vary the spacing between said dipoles, and means for rotating said antenna array to any angular position.

4. An antenna array for ultra-high frequency

75 of said director and reflector dipoles for support-

electromagnetic waves comprising a housing member, a principal dipole extending therefrom, a director dipole, a reflector dipole, each of said dipoles including two oppositely extending telescoping arms, spaced telescoping insulating connecting members extending from said housing to the midportions of said director and reflector dipoles and from the ends of said principal dipole to the ends of said director and reflector dipoles for supporting said director dipole and said reflector dipole in parallel relation to said principal dipole, a motor in said housing for driving the connecting member extending from said housing to change the spacing of said dipoles, and another motor connected to the arms of said principal dipole for changing their length and moving the connecting members connected thereto for changing the length of said other dipoles.

5. An antenna array for ultra-high frequency electromagnetic waves comprising a housing member, a first dipole extending therefrom, a second dipole, a third dipole, each of said dipoles including two oppositely disposed extensible arms, spaced extensible insulating connecting members extending from said housing to the midportions of said second and third dipoles and from the ends of said first dipole to the ends of said second and third dipoles for supporting said second dipole and said third dipole in parallel relation to said first dipole, a motor in said housing for driving the connecting member extending from said housing to change the spacing of said dipoles, and another motor connected to the arms of said first dipole for changing their length and moving the connecting members connected thereto for changing the length of said other dipoles.

6. An antenna array for ultra-high frequency electromagnetic waves comprising a housing member, a principal dipole extending therefrom, a director dipole, a reflector dipole, each of said dipoles including two oppositely extending telescoping arms, spaced telescoping insulating connecting members extending from the ends of said principal dipole to the ends of said director and reflector dipoles for supporting said director dipole and said reflector dipole in parallel relation to said principal dipole and a motor connected to the arms of said principal dipole for changing their length and moving the connecting members connected thereto for changing the length of said other dipoles.

7. An antenna array for ultra-high frequency electromagnetic waves comprising a housing member, a first dipole extending therefrom, a second dipole, a third dipole, each of said dipoles including two oppositely disposed extensible arms, spaced extensible insulating connecting members extending from the ends of said first dipole to the ends of said second and third dipoles for supporting said second dipole and said third dipole in parallel relation to said first dipole and a motor connected to the arms of said first dipole for changing their length and moving the connecting members connected thereto for changing the length of said other dipoles.

8. An antenna array for ultra-high frequency electromagnetic waves comprising a housing member, a principal dipole extending therefrom, a director dipole, a reflector dipole, each of said dipoles including two oppositely extending arms, spaced telescoping insulating connecting members extending from said housing to the midportions of said director and reflector dipoles and from the ends of said principal dipole to the ends of said director and reflector dipoles for support-

ing said director dipole and said reflector dipole in parallel relation to said principal dipole and a motor in said housing for driving the connecting member extending from said housing to change the spacing of said dipoles.

9. An antenna array for ultra-high frequency electromagnetic waves comprising a housing member, a first dipole extending therefrom, a second dipole, a third dipole, each of said dipoles including two oppositely extending arms, spaced telescoping insulating connecting members extending from said housing to the mid- portions of said second and third dipoles and from the ends of said first dipole to the ends of said second and third dipoles for supporting said second dipole and said third dipole in parallel relation to said first dipole and a motor in said housing for driving the connecting member extending from said housing to change the spacing of said dipoles.
